UNITED STATES PATENT OFFICE

92,926

DESIGN FOR A SPECTACLE FRAME FOR EYEGLASSES OR SIMILAR ARTICLES

Edwin Reynolds, Vineland, N. J.

Application February 24, 1934, Serial No. 50,852

Term of patent 14 years

To all whom it may concern:

Be it known that I, EDWIN REYNOLDS, a citizen of the United States, residing at Vineland, in the county of Cumberland, and State of New Jersey, have invented a new, original, and ornamental Design for a Spectacle Frame for Eyeglasses or Similar Articles, of which the following is a specification, reference being had to the accompanying drawing, forming part thereof.

Fig. 1 is a front perspective view of a spectacle

frame for eyeglasses or similar articles, showing my new design; and

Figs. 2 and 3 are, respectively, a rear perspective view and a top plan view with the temples omitted, for convenience of illustration.

I claim.

The ornamental design for a spectacle frame for eyeglasses or similar articles, substantially as shown and described.

EDWIN REYNOLDS.
